his ATTORNEY.

UNITED STATES PATENT OFFICE.

LEE R. WETHERILL, OF PHILADELPHIA, PENNSYLVANIA, ASSIGNOR TO STOKES AND SMITH COMPANY, OF PHILADELPHIA, PENNSYLVANIA, A CORPORATION OF PENNSYLVANIA.

FORM BLOCK.

Application filed January 14, 1924. Serial No. 686,240.

To all whom it may concern:

Be it known that I, LEE R. WETHERILL, a citizen of the United States, residing in the city and county of Philadelphia, State of Pennsylvania, have invented certain new and useful Improvements in Form Blocks, of which the following is a specification.

My invention relates to form blocks, of the character employed in machines, for example of the character described in Letters Patent No. 691,329, January 14, 1902, for covering previously formed or stayed boxes and their covers by applying thereto a cover blank, or for forming a box blank into box form and applying a cover blank serving both to hold the box blank elements in box-forming position and to cover the box.

In accordance with my invention, a form block, having a body of wood or any other suitable material, is provided at its corners with shoes of metal or other suitably hard wear-resisting material, having box-engaging faces whose planes coincide with or are adjustable with respect to the planes of the side box-engaging faces of the form blank body, or whose planes coincide with or are adjustable with respect to the planes of faces of side shoes, of metal or other suitably hard wear-resisting material, carried by the form blank body and preferably adjustable thereon.

For an illustration of some of the various forms my invention may take, reference is to be had to the accompanying drawings, in which:

Fig. 1 is a vertical sectional view, partly in elevation, illustrating one of the forms of my form block structure in its environment with the usual co-acting elements of a box-forming or covering machine.

Fig. 2 is a top plan view of a form block embodying my invention.

Fig. 3 is a sectional view, on larger scale, taken on the line 3—3 of Fig. 2.

Fig. 4 is a perspective view of the block shown in Fig. 2, one of the corner blocks being omitted.

Fig. 5 is a perspective view of a corner shoe.

Fig. 6 is a vertical sectional view, parts in elevation, in general similar to Fig. 1,

but including a modified form of form-block structure.

Fig. 7 is a top plan view of a modified form of form block embodying my invention.

Fig. 8 is a sectional view, on larger scale, taken on the line 8—8 of Fig. 7.

Fig. 9 is a perspective view of the form block in Fig. 7, with corner and side shoes removed.

Figs. 10 and 11 are perspective views of the corner and side shoes respectively.

Referring to Fig. 1, the form block plunger is shown as comprising, as usual, the associated and co-acting form blocks A and B controlled, as well understood in the art, by the rods 1 and 2, 2. The lower block A carries pins 3 passing loosely through holes 4 in the block B for holding them in proper register with each other but permitting their relative movement. The form blocks co-operate with the usual vertically movable platen 5, upon which are placed the box and cover blanks suitably manipulated by such tools or instrumentalities of the box-forming or covering machine, as brushes, rollers, corner lap fingers, edge turn-in fingers and pressure blocks.

In Fig. 1 the box and cover are indicated at 6, the cycle of operation having reached that stage at which the pressure blocks 7 are about to act.

Referring now to Figs. 2 to 5 inclusive, the form block B consists of a body having the lateral box-engaging faces 8, at its sides and ends.

The body or block B is preferably of wood or equivalent light and soft material, though it may be of metal or other material if suitable or desirable. It is preferred however, that the block B shall be light in weight to reduce the inertia of the moving parts of the machine whereby high speed operation is more readily attainable. At

its center there is secured to the block B by screws 9 the metal plate 10, into which are threaded at 11 the aforesaid rods 2, 2, for controlling vertical movement of the block B independently of or in suitably timed relation with respect to the lower form block A.

As indicated in Fig. 1, there is secured to the upper side of the block A a plate 12 to which is attached the rod 1 which extends through the hole 13 in the plate 10 and through the registering hole 14, in block 5 B, the latter terminating at the recess 15, in block B, to receive and accommodate the aforesaid plate 12.

At each of its corners the block B is cut 10 away, as indicated at 16, Fig. 4, to receive and accommodate the box-engaging cheeks 15 of the corner shoes 18. The shoes 18, and particularly their cheeks or flanges 17, are of metal or other suitably hard wear-resisting material, as molded phenolic condensation product, as bakelite, or equivalent. The body portion 18 of the corner shoe is 20 preferably in plate form engaging upon the upper surface of the block B, and confined thereto by the screws or bolts 19 extending upwardly through the block B, and having threaded on their upper ends the nuts 20 between which and the shoe body 18 may intervene resilient or locking 25 washers 21.

Each shoe 18 is provided with apertures 22 through which freely extend the aforementioned screws or bolts 19 and the fastening screw 23, threading into the body B for holding the shoe 18 in any position to which adjusted, the adjustability being permitted by the apertures 22, which, as indicated in Fig. 5, preferably extend diagonally or at 45 degrees with respect to the box-engaging faces 24 of the cheeks 17. By the adjustability described, the planes of the box-engaging faces 24 may be brought into coincidence with the planes of the box-engaging faces 8 of the body or block B, or the faces 24 may be adjusted to positions slightly short of or beyond the faces 8.

As indicated in Fig. 1, the blocks A and B may be provided with registering or aligned holes 25, 25, to accommodate the stripping rods, not shown, for stripping the box 6 from the form block structure upon completion of the cycle of operations performed by the machine.

As indicated, the shoes 18 may be provided with holes 26 in alignment with the holes 25. The block B may have the additional stripping rod holes 27, or both sets of holes 25 and 27 may be provided.

The corner shoes 18 co-act with the box and box wrapper or cover at regions where the adhesive, as glue, by which the wrapper or cover is held to the box, is to some extent pressed out and accordingly accumulates upon the form block, particularly adjacent its corners. Where the form block B is of wood or similar material, the repeated scraping of the box-engaging faces of the block to remove the accumulations of glue, will wear it away and deform it. The hard or metallic corner shoes however, of the

character described, withstand the wear incident to removal of accumulations of glue by scraping. The longitudinal extent of each of the cheeks or faces 17 or 24 may be made anything suitable or desirable. The minimum length however, should preferably be such as to extend throughout the region where the adhesive accumulates and on the other hand may be so great as to cause the cheeks or flanges 17 of neighboring corner shoes to meet.

In Fig. 6 there is shown substantially the same combination of parts indicated in Fig. 1, except that the form block B is supplied with additional box-engaging members 28, carried, as indicated in Figs. 7 to 9 inclusive, by the body B, of wood or other suitable material, between the corner shoes 18. The body 28 of each of these sides is preferably in the form of a plate overlying the upper face of the body B and having the downwardly extending cheek or flange 29 disposed adjacent the side or end face 30 of the block B. Each member 28 is provided with a plurality of slots 31, preferably open ended and through which extend bolts or screws 19, extending upwardly through the block B from its lower face and having applied thereto the nuts 20 and washers 21 as hereinbefore described. Through some of the slots 31 of members 28 may extend screws 23 for holding the members 28 in any position to which adjusted.

The cheeks or flanges 29 have the box-engaging faces 32, whose planes may be brought by adjustment to coincide with or to fall slightly short of or to extend slightly beyond the planes of the faces 24 of the corner shoes 18. As indicated in Figs. 7, 9 and 10, some of the corner shoes 18 may have elongated cheeks or flanges 17a which, with corner shoes having cheeks 17 of substantially equal length, and with side shoes of different lengths, will serve in different combinations to provide corner and side slices for blocks of different sizes operating upon boxes of different lengths and widths.

By structure of the character indicated in Figs. 7 to 9 inclusive, all of the box-engaging faces are the surfaces of members of metal or other hard wear-resisting material, and none of the side or end faces of the body or block B come into contact with the box or its wrapper.

The adjustments of the corner shoes of Figs. 2, 3 and 4, and the adjustments of the corner and side shoes of Figs. 7, 8 and 9, serve in addition to accommodate the form block structure to inaccuracies or irregularities in the creasing or scoring of the box blanks, for it sometimes occurs that the creasing or scoring is such that a perfectly rectangular box is not formed, and by adjustment of the shoes of the form block

structure, the outline of the form block structure may vary sufficiently from strictly rectangular form suitably to operate upon inaccurately scored box blanks and the resultant irregular box forms.

5 What I claim is:

1. Form block structure comprising a block, and a corner shoe carried by said block, said shoe having a body overlying said block, and a cheek having a box-engaging face disposed in a plane substantially parallel with a lateral face of said block.

10 2. Form block structure comprising a block, and a corner shoe carried by said block, said shoe having a body overlying said block, and cheeks disposed at an angle with each other and having box-engaging faces substantially parallel with lateral faces of said block.

20 3. Form block structure comprising a block, having its lateral faces recessed at a corner, and a corner shoe at said corner, having cheeks disposed in the recessed lateral faces of said block.

25 4. Form block structure comprising a block and a corner shoe carried by and diagonally adjustable upon said block.

30 5. Form block structure comprising a block, and a corner shoe having a body overlying said block and having a depending cheek whose face is substantially parallel with a lateral face of said block, and means for effecting adjustment of said cheek with respect to said lateral face.

35 6. Form block structure comprising a block, and a corner shoe having a body overlying said block and having a depending cheek whose face is substantially parallel with a lateral face of said block, and means for adjusting said shoe diagonally with respect to said lateral face of said block.

40 7. Form block structure comprising a block, and a corner shoe having intersecting faces, and means for adjusting said shoe diagonally upon said block.

45 8. Form block structure comprising a block, having its lateral faces recessed at a corner, and a corner shoe at said corner, having cheeks disposed in the recessed lateral faces of said block, and means for adjusting said shoe upon said block.

50 9. Form block structure comprising a block, having its lateral faces recessed at a corner, and a corner shoe at said corner, having cheeks disposed in the recessed lateral faces of said block.

55 10. Form block structure comprising a block member, a corner shoe member, one of said members having a diagonal slot, and means carried by the other of said members extending through said slot for securing said members to each other.

60 11. Form block structure comprising a block member a shoe member, one of said members having a plurality of slots, means

carried by the other of said members extending through one of said slots and holding said members for slidable engagement with each other, and means carried by said other of said members engaging in another of said slots for fixedly holding said members to each other in position to which relatively adjusted.

65 12. Form block structure comprising a block member, a corner shoe member, one of said members having a plurality of diagonally extending substantially parallel slots, means carried by the other of said members engaging in one of said slots to permit sliding adjustment of said members with respect to each other, and means carried by said other of said members engaging in another of said slots for fixedly holding said members in position to which relatively adjusted.

70 13. Form block structure comprising a block having an aperture to accommodate a stripping rod, and a shoe carried by and adjustable with respect to said block and having an aperture registering with said aperture in said block.

75 14. Form block structure comprising a block having at a corner an aperture to accommodate a stripping rod, and a corner shoe carried by and adjustable upon said block and having an aperture registering with said aperture in said block.

80 15. Form block structure comprising a body of soft material, such as wood or equivalent, and a shoe of hard wear-resisting material, such as metal or equivalent, carried thereby.

85 16. Form block structure comprising a body of soft material, such as wood or equivalent, said body having lateral box-engaging faces, and a corner shoe, of metal or equivalent material, adjustable diagonally upon said body and having depending cheeks whose faces are substantially parallel with said lateral faces of said body.

90 17. Form block structure comprising a block, and a side shoe of hard wear resisting material carried by said block and terminating short of the corners of said block.

95 18. Form block structure comprising a block, and a side shoe carried by said block and terminating short of the corners of said block, and means for adjusting said shoe laterally of block.

100 19. Form block structure comprising a block, and independent corner and side shoes carried by said block.

105 20. Form block structure comprising a block, and independent corner and side shoes carried by said block, and means for adjusting said corner and side shoes upon said block.

110 21. Form block structure comprising a block, and independent corner and side shoes carried by said block, and means for adjusting said corner blocks diagonally up-

- on said block, and means for adjusting said side shoe in a direction at right angles to the side of said block to which said side shoe is applied.
- 5 22. Form block structure comprising a body member of wood or equivalent material, and independent corner and side shoes of metal or equivalent material carried by said body and having box-engaging faces disposed in substantially the same plane.

23. Form block structure comprising a body member, corner shoes carried by said body member at adjacent corners thereof, each of the said corner shoes having depending cheeks having box-engaging faces, the cheeks of one of said corner shoes having unequal lengths, and a side shoe carried by said body member between said corner shoes. ¹⁵

LEE R. WETHERILL.
